UNITED STATES PATENT OFFICE.

ELZIVER O. RICKARD, OF SYRACUSE, NEW YORK, ASSIGNOR TO THE
KELSEY FURNACE COMPANY, OF SYRACUSE, NEW YORK.

FURNACE.

SPECIFICATION forming part of Letters Patent No. 705,965, dated July 29, 1902.

Application filed March 6, 1900. Serial No. 7,463. (No model.)

To all whom it may concern:

Be it known that I, ELZIVER O. RICKARD, of Syracuse, in the county of Onondaga, in the State of New York, have invented certain 5 new and useful Improvements in Furnaces, of which the following is a specification.

My invention relates to improvements in furnaces for heating air, and has for its object the production of a device for the desired 10 purpose which is strong and durable in use, simple in construction, and highly efficient in operation; and to this end it consists in the combination, construction, and arrangement of the component parts of a furnace, as 15 hereinafter fully described, and pointed out in the claims.

In describing this invention reference is had to the accompanying drawings, forming part of this specification, in which like letters indicate corresponding parts in all the views.

Figure 1 is a vertical sectional view, partly broken away, of my improved furnace. Fig. 2 is an elevation, partly in section, of the parts illustrated in Fig. 1, the outer shell, 25 the cold-air chamber, and the ash-box being removed. Fig. 3 is a horizontal sectional view taken on line 3 3, Fig. 2.

My improved furnace consists, essentially, of a combustion-chamber A, an ash-box B, a 30 cold-air chamber C, air-heating conduits and chambers D D' D², a water-heating chamber E, a chamber F for receiving the products of combustion, and an outer shell G. The combustion-chamber A is of any desirable form 35 and size, being here illustrated as cylindrical and as inclosed by the air-heating conduits and chamber D D', the water-heating chamber E, and upper and lower separable plates a a' and as communicating with a fuel-inlet 40 passage a², extending rearwardly from the front of the furnace. Said plates a a' project outwardly beyond the combustion-chamber A, are provided with detachable central portions a³ a⁴ and with openings a⁵, extending 45 vertically through their outer portions and alined with each other, and are united together by inner and outer series of bolts a⁶ a⁷, engaged, respectively, with the inner and outer portions of said plates and passed 50 through the conduits D, presently described.

The opposing faces of the plates a a' are

formed with substantially vertical projecting shoulders a⁸ a⁹ and flanges a¹⁰ a¹¹, the flange a¹⁰ of the upper plate a being extended downwardly and formed of less diameter than said 55 plate and the flange a¹¹ of the lower plate a' being extended upwardly and formed of greater height than the flange a¹⁰ and being provided with an outwardly-projecting peripheral shoulder a¹². Said flange a¹¹ is also 60 provided with an opening a¹³, extending horizontally through its front part beneath the shoulder a¹², and with outwardly-projecting tubular branches or extensions a¹⁴, arranged beneath said shoulder a¹², one or more of the 65 branches or extensions a¹⁴ being provided with a suitable closure a¹⁵ and serving as clean-out openings and another of the branches or extensions being connected to any desirable smoke-conduit H.

The ash-box B is arranged beneath the combustion-chamber A and extends forwardly beyond said chamber A, the top b of the forwardly-extending part of the ash-box being depressed beneath the contiguous portion of 75 the plate a', previously described. The cold-air chamber C partly incloses the ash-box B and extends upwardly above the forwardly-projecting part of said ash-box.

The air-heating conduits and chamber D 80 D' extend vertically around the combustion-chamber A. Said conduits D are arranged at opposite sides of the fuel-inlet passage a², are of substantially uniform length, communicate at their opposite ends with adjacent 85 openings a⁵ in the plates a a', previously described, and are provided at their ends with shoulders d, engaged with the shoulders a⁸ a⁹ of the plates a a'. The conduits D form the upright inclosing wall for part of the combustion-chamber A, and, as best seen in Fig. 1, the lower portions of the contiguous sides of adjacent conduits D are substantially flat and in contact with each other, and the upper portions of said sides are corrugated and 90 separated for forming corrugated heating-surfaces within the conduits D and corrugated passages or flues d', leading from the combustion-chamber A between the conduits D to the chamber F, presently described.

The air-heating chamber D' is formed with an open top communicating with one of the

openings a^5 of the upper plate a . The air-heating chamber D^2 is arranged at the outside of the water-heating chamber E , presently described, beneath the fuel-inlet passage a^2 and above the forwardly-projecting part of the ash-box B , and is formed with its bottom and front sides open for communicating, respectively, with one of the openings a^5 of the plate a' and the opening a^{13} of the flange a^{11} , said openings a^5 a^{13} thus forming, essentially, upper and lower circulating openings for the chamber D^2 .

The chamber E is detachably arranged at the inner side of the chamber D^2 beneath the fuel-inlet passage a^2 and upon the lower plate a' between the conduits D , arranged at opposite sides of said fuel-inlet passage, and forms the upright inclosing wall of the part of the combustion-chamber A not inclosed by the conduits and chamber D D' . Said chamber E is usually provided with a supplemental water-heating chamber e , projecting from its inner face into the combustion-chamber, and is connected to water-circulating pipes e' e^2 , extending through the air-heating chamber D^2 , one of said pipes being arranged above the flange a^{11} and the other being passed through the opening a^{13} in said flange.

The chamber F is inclosed by the upper and lower plates a a' , previously described, a tubular shell f , and the outer walls of the conduits and chamber D D' . Said shell f is suitably connected to the smoke-conduit H , surrounds the flange a^{10} of the plate a and the upper portion of the flange a^{11} , and its end edges are engaged with the upper plate a and the shoulder a^{12} of the lower plate a' .

The outer shell G is of any desirable form, size, and construction and receives the air heated by my furnace.

In my pending application, Serial No. 4,164, filed February 6, 1900, I have disclosed and claimed a construction of furnace similar to that forming the subject-matter hereof, but unprovided with the heating-chamber E , the supplemental water-heating chamber e , and the water-circulating pipes e' e^2 .

The construction and operation of my furnace will now be readily understood upon reference to the foregoing description and the accompanying drawings, and it will be obvious that more or less change may be made in the detail construction and arrangement of its component parts without departing from the spirit of my invention.

Having thus fully described my invention, what I claim as new, and desire to secure by Letters Patent, is—

1. In a furnace, the combination of upper and lower separable plates having openings extending vertically therethrough, a tubular shell interposed between the upper and lower plates, upright air-heating conduits forming the upright wall of a part of the combustion-chamber of the furnace, said conduits being arranged between the upper and lower plates within the tubular shell and communicating

with the openings in said plates, and a water-heating chamber also forming the upright wall of a part of the combustion-chamber, 70 said water-heating chamber being arranged within the tubular shell between two of the air-heating conduits, substantially as and for the purpose described.

2. In a furnace, the combination of upper 75 and lower separable plates having openings extending vertically therethrough, the lower plate being provided with an upwardly-extending flange, a tubular shell interposed between the upper plate and the upwardly- 80 extending flange of the lower plate, upright air-heating conduits forming the upright wall of a part of the combustion-chamber of the furnace, said conduits being arranged between the upper and lower plates within the 85 tubular shell at the inner side of the upwardly-extending flange of the lower plate and communicating with the openings in said plates, and a water-heating chamber also forming the upright wall of a part of the combustion-chamber, 90 said water-heating chamber being detachably mounted on the lower plate within the tubular shell at the inner side of said upwardly-extending flange and between two of the air-heating conduits, substantially 95 as and for the purpose specified.

3. In a furnace, the combination of upper and lower separable plates having openings extending vertically therethrough, the upper plate being provided with a downwardly-extending flange of less diameter than said plate, and the lower plate being provided with an upwardly-extending flange having a peripheral shoulder, a tubular shell surrounding the depending flange on the upper plate 105 and the upper portion of the flange on the lower plate and interposed between the upper plate and the peripheral shoulder of the flange on the lower plate, upright air-heating conduits forming the upright wall of a part of the combustion-chamber, 110 said conduits being arranged between the upper and lower plates within the tubular shell at the inner sides of said flanges of the upper and lower plates and communicating with the openings in said plates, and a water-heating chamber also forming the upright wall of a part of the combustion-chamber, 115 said water-heating chamber being mounted on the lower plate within the tubular shell at the inner side of the upwardly-extending flange of said lower plate and between two of the air-heating conduits, 120 substantially as set forth.

4. In a furnace, the combination of upper and lower separable plates having openings 125 extending vertically therethrough, a tubular shell interposed between the upper and lower plates, upright air-heating conduits forming the upright wall of a part of the combustion-chamber of the furnace, said conduits 130 being arranged between the upper and lower plates within the tubular shell and communicating with the openings in said plates, a water-heating chamber also forming the up-

right wall of a part of the combustion-chamber, said water-heating chamber being arranged within the tubular shell between two of the air-heating conduits, and a supplemental water-heating chamber projecting from the inner face of the former water-heating chamber into said combustion-chamber, substantially as and for the purpose set forth.

- 10 5. In a furnace, the combination of upper and lower separable plates having openings extending vertically therethrough, the lower plate being provided with an upwardly-extending flange, a tubular shell interposed be-
15 tween the upper plate and the upwardly-extending flange of the lower plate, upright air-heating conduits forming the upright wall of a part of the combustion-chamber of the furnace, said conduits being arranged between
20 the upper and lower plates within the tubular shell at the inner side of the upwardly-extending flange of the lower plate and communicating with the openings in said plates, a water-heating chamber also forming the
25 upright wall of a part of the combustion-chamber, said water-heating chamber being detachably mounted on the lower plate within the tubular shell at the inner side of said upwardly-extending flange and between two
30 of the air-heating conduits, and a supplemental water - heating chamber projecting from the inner face of the former water-heating chamber into said combustion-chamber, substantially as and for the purpose de-
35 scribed.

6. In a furnace, the combination of upper and lower separable plates having openings extending vertically therethrough, a tubular shell interposed between the upper and lower plates, upright air-heating conduits forming the upright wall of a part of the combustion-chamber of the furnace, said conduits being arranged between the upper and lower plates within the tubular shell and communicating with the openings in said plates and having the lower portions of their contiguous sides formed substantially flat and engaged with each other, and the upper portions of said sides corrugated and separated, and a water-heating chamber also forming the upright wall of a part of said combustion-chamber and arranged within the tubular shell between two of the air-heating conduits, substantially as and for the purpose specified.

- 55 7. In a furnace, the combination of upper and lower separable plates having openings extending vertically therethrough, the lower plate being provided with an upwardly-extending flange, a tubular shell interposed between the upper plate and the upwardly-extending flange of the lower wall, upright air-heating conduits forming the upright wall of a part of the combustion-chamber of the furnace, said conduits being arranged between the upper and lower plates within the tubular shell at the inner side of the upwardly-extending flange of the lower plate and com-

60

65

communicating with the openings in said plates, a water-heating chamber also forming the upright wall of a part of said combustion-chamber, said water-heating chamber being detachably mounted on the lower plate within the tubular shell at the inner side of said upwardly-extending flange and between two of the air-heating conduits, and water-circulating pipes connected to the water-heating chamber, one of the pipes being arranged above said upwardly-extending flange, and the other being passed through said flange, substantially as and for the purpose set forth. 80

8. In a furnace, the combination of upper and lower separable plates having openings extending vertically therethrough, the lower plate being provided with an upwardly-extending flange, a tubular shell interposed between the upper plate and the upwardly-extending flange of the lower plate, upright air-heating conduits forming the upright wall of a part of the combustion-chamber of the furnace, said conduits being arranged between the upper and lower plates within the tubular shell at the inner side of the upwardly-extending flange of the lower plate and communicating with the openings in said plates, a water-heating chamber also forming the upright wall of a part of said combustion-chamber, said water-heating chamber being detachably mounted on the lower plate within the tubular shell at the inner side of said upwardly-extending flange and between two of the air-heating conduits, a supplemental water-heating chamber projecting from the inner face of the former water-heating chamber into said combustion-chamber, and water-circulating pipes connected to the water-heating chamber, one of the pipes being arranged above said upwardly-extending flange, and the other being passed through said flange, substantially as and for the purpose described. 85 90 95 100 105 110

9. In a furnace, the combination of upper and lower separable plates having openings extending vertically therethrough, a tubular shell interposed between the upper and lower plates, upright air-heating conduits forming the upright wall of a part of the combustion-chamber of the furnace, said conduits being arranged between the upper and lower plates within the tubular shell and communicating with the openings in said plates, a water-heating chamber also forming the upright wall of a part of the combustion-chamber, said water-heating chamber being arranged within the tubular shell between two of the air-heating conduits, and an air-heating chamber arranged within the tubular shell at the outer side of the water-heating chamber, substantially as and for the purpose specified. 115 120 125

10. In a furnace, the combination of upper and lower separable plates having openings 135 extending vertically therethrough, the lower plate being provided with an upwardly-extending flange, a tubular shell interposed between the upper plate and the upwardly-ex-

- tending flange of the lower wall, upright air-heating conduits forming the upright wall of a part of the combustion-chamber of the furnace, said conduits being arranged between the upper and lower plates within the tubular shell at the inner side of the upwardly-extending flange of the lower plate and communicating with the openings in said plates, a water-heating chamber also forming the upright wall of a part of the combustion-chamber, said water-heating chamber being detachably mounted on the lower plate within the tubular shell at the inner side of said upwardly-extending flange and between two of the air-heating conduits, and an air-heating chamber arranged within the tubular shell between said upwardly-extending flange and the water-heating chamber, substantially as and for the purpose set forth. 5

11. In a furnace, the combination of upper and lower separable plates having openings extending vertically therethrough, the lower plate being provided with an upwardly-extending flange, a tubular shell interposed between the upper plate and the upwardly-extending flange of the lower plate, upright air-heating conduits forming the upright wall of a part of the combustion-chamber of the furnace, said conduits being arranged between the upper and lower plates within the tubular shell at the inner side of the upwardly-extending flange of the lower plate and communicating with the openings in said plates, a water-heating chamber also forming the upright wall of a part of the combustion-chamber, said water-heating chamber being detachably mounted on the lower plate within the tubular shell at the inner side of said upwardly-extending flange and between two of the air-heating conduits, an air-heating chamber arranged within the tubular shell between said upwardly-extending flange and the water-heating chamber, a supplemental water-heating chamber projecting from the inner face of the former water-heating chamber into said combustion-chamber, and water-circulating pipes passed through the air-heating chamber and connected to the water-heating chamber, one of the pipes being arranged above said upwardly-extending flange, and the other being passed through said flange, substantially as and for the purpose described 45

12. In a furnace, the combination of upper and lower separable plates having openings extending vertically therethrough and aligned with each other, the lower plate being provided with an upwardly-extending flange formed with an opening extending horizontally therethrough, a tubular shell interposed between the upper plate and the upwardly-extending flange of the lower plate, upright air-heating conduits forming the upright wall of a part of the combustion-chamber of the furnace, said conduits being arranged between the upper and lower plates within the tubular shell at the inner side of the upwardly-extending flange of the lower plate and communicating with the openings in said plates, a water-heating chamber also forming the upright wall of a part of the combustion-chamber, said water-heating chamber being detachably mounted on the lower plate within the tubular shell at the inner side of said upwardly-extending flange and between two of the air-heating conduits, and an air-heating chamber arranged within the tubular shell between said upwardly-extending flange and the water-heating chamber, substantially as and for the purpose set forth. 50

13. In a furnace, the combination of upper and lower separable plates having openings extending vertically therethrough and aligned with each other, the lower plate being provided with an upwardly-extending flange formed with an opening extending horizontally therethrough, a tubular shell interposed between the upper plate and the upwardly-extending flange of the lower plate, upright air-heating conduits forming the upright wall of a part of the combustion-chamber of the furnace, said conduits being arranged between the upper and lower plates within the tubular shell at the inner side of the upwardly-extending flange and between two of the air-heating conduits, an air-heating chamber arranged within the tubular shell between said upwardly-extending flange and the water-heating chamber, and formed with upper and lower openings communicating with one of the openings extending vertically through the lower plate and with the opening extending horizontally through the upwardly-extending flange of said lower plate, substantially as and for the purpose specified. 55

14. In a furnace, the combination of upper and lower separable plates having openings extending vertically therethrough and aligned with each other, the lower plate being provided with an upwardly-extending flange formed with an opening extending horizontally therethrough, a tubular shell interposed between the upper plate and the upwardly-extending flange of the lower plate, upright air-heating conduits forming the upright wall of a part of the combustion-chamber of the furnace, said conduits being arranged between the upper and lower plates within the tubular shell at the inner side of the upwardly-extending flange and between two of the air-heating conduits, an air-heating chamber arranged within the tubular shell between said upwardly-extending flange and the water-heating chamber, and formed with upper and lower openings communicating with one of the openings extending vertically through the lower plate and with the opening extending horizontally through the upwardly-extending flange of said lower plate, substantially as and for the purpose set forth. 60

In testimony whereof I have hereunto signed my name, in the presence of two attesting witnesses, at Syracuse, in the county of Onondaga, in the State of New York, this 12th day of January, 1900.
